UNITED STATES PATENT OFFICE.

GILBERT L. CROWELL, JR., OF ARLINGTON, NEW JERSEY, ASSIGNOR TO DOMINICK & HAFF, OF NEW YORK, N. Y., A JOINT STOCK COMPANY OF NEW YORK.

DESIGN FOR A SPOON, FORK, OR SIMILAR ARTICLE.

40,833.

Specification for Design.

Patented Aug. 23, 1910.

Application filed April 21, 1910. Serial No. 556,902. Term of patent 7 years.

To all whom it may concern:

Be it known that I, GILBERT L. CROWELL, Jr., a citizen of the United States, and a resident of Arlington, in the county of Hudson and State of New Jersey, have invented a new, original, and ornamental Design for a Spoon, Fork, or Similar Article, of which the following is a specification, reference being had to the accompanying drawing, forming part thereof.

The figure is a plan view showing my improved design.

I claim:

The ornamental design for a spoon, fork, or similar article, as shown.

GILBERT L. CROWELL, Jr.
